UNITED STATES PATENT OFFICE.

FERDINAND KAISER, OF ST. PAUL, MINNESOTA, ASSIGNOR OF ONE-HALF TO GEORGE B. LEONARD, OF MINNEAPOLIS, MINNESOTA.

PENCIL.

Application filed November 28, 1921. Serial No. 518,175.

To all whom it may concern:

Be it known that I, FERDINAND KAISER, a citizen of the United States, residing at St. Paul, in the county of Ramsey and State of Minnesota, have invented certain new and useful Improvements in Pencils; and I do hereby declare the following to be a full, clear, and exact description of the invention, such as will enable others skilled in the art 10 to which it appertains to make and use the same.

My invention relates to that type of mechanically operated lead pencil that is especially adapted to use marking leads of such small diameter that sharpening thereof is not required; and the object of my invention is to provide a pencil of the above type which will be of neat or ornamental appearance, durable, easily operated and 20 generally satisfactory for the purposes had in view and which may be manufactured at a minimum of cost.

Generally stated, these objects I accomplish by the construction, arrangement and 25 combinations defined in the claims and the preferred form of which pencil is illustrated in the accompanying drawings and particularly described in the specification.

A commercial form of this improved pencil is illustrated in the accompanying drawings, wherein like characters indicate like parts throughout the several views.

Referring to the drawings:

Fig. 1 is a plan view of the improved pencil, some parts being sectioned and the pencil being shown on an enlarged scale;

Fig. 2 is an axial section on the line 2—2 of Fig. 1;

Fig. 3 is a perspective showing all of the 40 parts of the pencil except the outer casing or barrel and which parts are removable from said outer casing or barrel;

Figs. 4, 5 and 6 are transverse sections taken, respectively, on the lines 4—4, 5—5 45 and 6—6 of Fig. 2;

Fig. 7 is a plan view showing the flat stamped sheet metal blank from which the so-called lead "pusher" and parts formed integral therewith are formed;

Fig. 8 is a perspective showing a modified form of the lead pusher; and

Fig. 9 is a transverse section taken on the line 9—9 of Fig. 8.

The construction illustrated in Figs. 1 to 55 7, inclusive, will first be described.

As a highly important feature of this invention, the tubular outer shell or barrel of the pencil is directly formed with a spiral thread in its main body portion. This outer shell 10, in practice, will be made from a thin metal tube and its threads 11 will be placed therein so that not only the interior but the exterior thereof will have the thread formation. The internal threads are for co-operation with the lead pusher, but the 60 external threads or spiral corrugation gives the exterior of the shell a formation that prevents the barrel from slipping in the hand and is especially important when the barrel is made with a polished surface or 65 plated. One end of the outer shell 10, as is usual, is conically contracted to form a small opening through which the small lead 70 y will pass with close engagement; but the other end of said shell 10 is cylindrical and 75 smooth.

The so-called lead pusher is of tubular form and has threaded engagement directly with the internal threads of the outer shell or barrel. As a highly important feature, 80 this lead pusher is constructed and adapted to serve the additional function of a magazine for holding stationary leads within the pencil. In the commercial form of the pencil, this combined lead pusher and magazine is made from a single piece of thin sheet metal first stamped as shown in Fig. 7 and then bent to form a tubular lead pusher 12 that also serves as a lead magazine. The edges of element 12 are spaced 85 to form an entrance slot 13. This tubular member 12 has outwardly pressed threads 14 that engage the internal threads of the outer tubular shell or barrel 10 and will be held frictionally engaged therewith by the 90 outward springing stress in said tubular member. The blank from which the tube 12 is made is formed at one end with a head-forming portion 15, with a slot 16 95 therein, and at its other end with head-forming portion 17 having an extension 18 100 with a widened outer end portion 19. In the completed device, the head-forming portions 15 and 17 are bent to close the ends of the tube 12; the extension 18 is bent to 105 form a tubular neck and the widened outer end portion 19 is bent to form a split tubular lead-holding socket that will frictionally clamp the operative lead y. The complete form of the combined lead pusher and 110

magazine is best shown in Fig. 3, by reference to which it will be seen that the tubular portion 12 is well adapted to hold a large number of extra leads. The portion 19 at the bottom socket is indented at 19^a to close the bottom of said socket.

For rotating the tubular combined lead pusher and magazine, I provide an operating stem 20, preferably in the form of a small flat metal bar, which works freely through the slot 16 of the head 15 and is provided with an expanded head 21 that can be passed through said slot 16 only when the parts shown in Fig. 3 are removed from the outer shell or barrel and said stem is moved to an angular position. An operating head 22 is shrunk, cast or otherwise rigidly secured to the trunnion-like outer end of the stem 20, and a cap-like sleeve 23 is swiveled on said outer end of the stem 20 immediately adjacent to the head 22, said stem being, as shown, flattened at 24 to hold the stem 20 against axial movement in respect to the sleeve 23 while free for rotation therein. The sleeve 23 is split and thereby made slightly expansible, to adapt it to be telescoped into the cylindrical end of the outer shell or barrel 10 and to be quite firmly frictionally clamped therein but capable of being removed, when the parts shown in Fig. 3 are to be removed from the barrel.

When the parts of the pencil are assembled as shown in Fig. 2, the frictionally held sleeve 23 affords a non-rotary bearing for the stem 20. Rotation of the stem 20 is, of course, produced by rotation of the operating head 22 and rotation of said stem causes rotation of the tubular combined lead pusher and magazine 12. Of course, rotation of the tubular combined lead pusher and magazine in one direction causes it to travel toward the tapered end of the outer shell, thereby projecting the lead, and rotation thereof in the opposite direction will cause the lead to be drawn into said outer shell.

To place a new lead in the socket 19, the parts shown in Fig. 3 will be removed from the outer shell or barrel and this may be readily done by rotating the tubular member 12 until its threads 14 are brought into the cylindrical outer end of the barrel and thereafter pulling on the head 22, thereby withdrawing the sleeve 23 and said member 12 from the barrel. Said parts shown in Fig. 3 may be quickly replaced by an operation substantially reversed from that just described.

The modified construction illustrated in Fig. 8 is like that already described except that the tubular member 12 is formed with diametrically opposite circumferentially spaced thread sections 25 and said tubular member 12 is provided on opposite sides of

said thread sections with slits 26 which make the opposite threaded portions very resilient and capable of being slipped within the threads of the barrel or outer shell 10, simply by axial pressure such as would be produced either by pressing the pencil against the projecting point of the lead or by pulling outward on the tubular member 12 by force applied thereto through the stem 20 and head 22. By the latter indicated operation, it is made an easy matter to quickly pull the entire internal mechanism of the pencil out of the outer shell or barrel 10 by direct or straight-line movement and without rotation of any of the parts and, of course, said parts may be replaced by a reverse straight-line movement.

The simplicity of the pencil described is obvious. As illustrated, it is made up entirely of five elements, to wit: the outer shell or barrel; the combined tubular lead pusher and magazine with its integrally connected parts; the operating stem 20; the operating head 22; and the frictionally held bearing sleeve 23. All of these parts may be commercially made at very low cost but the pencil produced by the assembled parts has all of the requisites of an efficient high grade pencil. Of course, the pencil and especially the outer shell or barrel and the exposed operating head may be made either of cheap metal, plated or otherwise finished or may be made of the more expensive materials, such as silver.

Pencils of the above type are very frequently used for advertising purposes and when so used require smooth space upon which an advertisement, such as a firm name or the name of some goods, may be printed, stamped or otherwise marked. Hence, in the preferred form of the pencil, the pressed spiral threads are extended from the conical end of the shell or barrel only about half way back, thereby leaving about one-half of the outer shell or barrel smooth for the purpose stated.

What I claim is:

1. A pencil comprising an outer shell having pressed internal threads, a resilient tubular combined lead pusher and lead magazine having pressed threads engageable with the pressed thread of said outer shell, an operating stem rotatable with said combined lead pusher and magazine but permitting the latter to slide thereon, and an operating head connected to the outer end of said operating stem, said combined lead pusher and magazine being made from a single piece of sheet metal bent to form a cylindrical magazine with threads thereon and with closed ends, one of the ends having an integral extension bent to form a stem terminating in a lead-receiving socket.

2. A pencil comprising an outer shell having pressed internal threads, a resilient tu-

bular combined lead pusher and lead magazine having pressed threads engageable with the pressed thread of said outer shell, an operating stem rotatable with said combined 5 lead pusher and magazine but permitting the latter to slide thereon, and an operating head connected to the outer end of said operating stem, the threads of said combined lead pusher being interrupted and the 10 thread sections being at diametrically opposite points and capable of being slipped within the threads of said outer shell by non-rotary sliding movements.

3. A pencil comprising an outer tubular shell, a lead pusher working with threaded engagement in the interior of the shell, a stem for rotating said lead pusher having a head exposed at the exterior of said shell, and an anchoring sleeve swivelled to said stem and frictionally engageable with the 15 interior of said shell, said stem being a flat bar having an upset portion holding said sleeve adjacent to said operating head with freedom for the swivel action stated.

In testimony whereof I affix my signature.
FERDINAND KAISER.
